UNITED STATES PATENT OFFICE

JOHN W. COOKE, OF COLGATE, MARYLAND

ESCAPE DEVICE FOR SUBMARINES

Application filed March 3, 1928. Serial No. 258,716.

This invention relates to submarines and has special reference to an escape device for submarine boats.

One important object of the invention is to provide an improved device of this character by means of which all of the persons who may be trapped in a sunken submarine may be carried to the surface of the water without danger and without subjecting them to pressure from the depth of the water in which the submarine may be sunk.

A second important object of the invention is to provide means of improved character for positively expelling a series of man carrying projectiles from a submarine.

A third important object of the invention is to provide means including a spring capable of being tensioned from within the submarine for producing the expulsion of such projection.

A fourth important object of the invention is to provide means whereby the release of such spring may be controlled from within a projectile.

With the above and other objects in view as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Figure 1 is a side elevation of a portion of a submerged submarine showing the water above it and certain of the projectiles as they appear on the surface.

Figure 2 is an enlarged vertical section through the expulsion apparatus of the submarine.

Figure 3 is a view similar to Figure 2 showing the spring expanded.

Figure 4 is a plan view of the valve closing the mouth of the expulsion tube.

Figure 5 is a bottom view of the expulsion tube.

In the present embodiment of the invention and in the drawings there is disclosed a portion of a submarine hull 10 and extended downward through a suitable opening in the top of this hull and secured firmly therein is a vertical tube 11 which projects slightly above the top of the hull as clearly seen in Figures 2 and 3. From one side of this upwardly projecting portion extends a bracket 12 to which is hinged a closure which seats on the upper end of the tube 11 and consists of a body portion 13 and a cushion or gasket 14 to render the closure watertight when thus seated. Obviously, the greater the pressure the more firmly will the closure be seated on the upper end of the tube but it is desirable to ensure the closing of the closure by means of a leaf spring 15 which is secured at one end to the hull 10 and bears at its other end on top of said closure.

Within the hull the tube 11 is cut away at one side to form an inlet opening 16 and extending from this inlet opening is a platform 70 or gallery 17 for supporting the man carrying projectiles. The lower end of the tube 11 is provided with a fixed closure 18 having an opening through its center through which extends the stem or piston rod 19 carrying on its upper end a piston 20 supporting an elastic pad or cushion 21. Between the piston 20 and the closure 18 is arranged a powerful coiled spring 22 which, when compressed, permits the pad 21 to sink to a level with the platform or gallery 17. At the lower end of the piston rod 19 is an eye 23 wherewith is detachably engageable a hook 24 on one end of a cable 25 which is led around a pulley 26 fixed in the hull of the submarine below the tube 11. On the bottom closure 18 is mounted a frame 27 in which is journaled a winding drum 28 around which the remaining end of the cable 25 is wound. On the 90

shaft of this drum 28 is fixed a gear 29 where-
with meshes a pinion 30 actuated by a crank
31 and provided with a swinging pawl 32.
By means of this apparatus it will be seen
that rotation of the crank 31 in the proper di-
rection will draw the piston rod 19 downward
and compress the spring 22, the spring being
held compressed at this time by the pawl 32.
In the piston rod 19 there is provided a notch
33 which is so located that when the spring
22 is compressed this notch lies just below
the closure 18 so that a flat lever 34, pivoted
on the bottom of the closure 18 to swing in a
horizontal plane, may swing into this notch
15 and thus lock the rod 19 from movement.
The lever 34 is urged to position in the notch
by means of a spring 35 but may be held
back from such position by means of a pin
36 chained by a chain 37 to the closure 18 in
order that it may be prevented from loss.

Each of the man carrying projectiles is
arranged to form a watertight closure and
is provided with a cylindrical body 38 closed
at its bottom by a flat plate 39 and at its top
25 by a conical hood or cover 40 having a heavy
sight glass 41 set therein. In one side of
the body is a door 42 which is hinged to the
body and may be locked closed by a closure
43. Of course, this door is arranged so that
30 it is watertight. One or more of these pro-
jectiles is provided at the side opposite the
door with an internally threaded boss 44
through which extends a locking screw 45
having an operating handle 46 and this screw
35 is provided with a point 47 which fits, when
projected, in a suitable opening 48 in the side
of the tube 11.

This locking screw is provided principally
for the final projectile to be expelled and
40 need only be used in this final projectile al-
though it may be provided with a number
of other projectiles.

In operation the people endeavoring to
escape from the submarine assemble around
45 the tube 11 and one of the men, by means
of the crank 31, compresses the spring 22.
Then one of the projectiles is shoved from
the gallery 17 onto the elastic pad 21, a man
enters through the door 42 and closes the
50 door. Meanwhile, the pawl 32 has been
turned back and the lever 34 allowed to en-
gage the notch 33. If desired the hook 24
may be detached from the point 23. When
the man is in position in the projectile and
55 the door closed one of the remaining men of
the crew releases the lever 34 from the notch
and the spring 22 expands, carries the pro-
jectile upwardly and the top of the projectile
strikes the closure 13, forces it open and
60 ascends to the surface of the water.

When it comes the turn of the last man to
escape he draws the piston downward and
compresses the spring as before. He then
65 goes into the last projectile and operates the
screw 45 to lock the projectile to the side of

the tube 11. He then releases the lever 34
and holds it released by the pin 36, leaving
the projectile to accomplish this. Finally
he returns to the projectile, shuts the door 42
and unscrews the screw 45 whereupon the
70 projectile is ejected as before.

There has thus been provided a simple and
efficient device of the kind described and for
the purpose specified.

It is obvious that minor changes may be
made in the form and construction of the
invention without departing from the ma-
terial spirit thereof. It is not, therefore,
desired to confine the invention to the exact
form herein shown and described, but it is
desired to include all such as properly come
within the scope claimed.

Having thus described the invention, what
is claimed as new, is:

1. An escape device for submarines in-
cluding an ejector tube having a loading
opening at one side, a man carrying pro-
jectile insertable through said opening re-
leasable means operable from within the pro-
jectile for engaging the tube and locking the
90 projectile to the tube, spring operated means
associated with said tube for ejecting the
projectile, means exterior of the tube for ten-
sioning said spring means, a latching device
on the exterior of the tube for engaging the
95 spring operated means and releasably re-
straining the same from operation, and a stop
device for holding the latching device out
of operation.

2. An escape device for submarines includ-
ing an ejector tube having a loading opening
at one side, a man carrying projectile insert-
able through said opening, spring operated
means associated with said tube for ejecting
the projectile, means exterior of the tube for
tensioning said spring means, a latching de-
vice on the exterior of the tube for engaging
the spring operated means and releasably re-
straining the same from operation, and a stop
device for holding the latching device out of
100 operation.

3. An escape device for submarines com-
prising in combination, a tube having the
upper end portion thereof projecting through
the top of the hull of a sunken vessel, said
tube being formed with a loading opening
115 in the side thereof, a floatable chamber insert-
able through said opening, a vertically mov-
able piston arranged within the lower por-
tion of the tube and constituting a support
120 for the floatable chamber, a piston rod con-
nected at its upper end to the piston and ex-
tending through the bottom of the tube, an
expansible coil spring encircling the piston
rod and disposed between the lower end of
125 the tube and said piston for normally urging
the piston upwardly to project the floatable
chamber outwardly through the upper end of
the tube, means for moving the piston rod
downwardly to compress the expansible coil
130

spring including a winding drum secured within the hull of the boat, a cable attached at one end to the lower end of the piston rod and at its opposite end to the drum and around which the same is to be wound, means for holding the piston rod in a lowered position to maintain the coil spring under compression, and a closure for the upper end of the tube movable to an open position by the floatable chamber when the latter is projected from the tube.

In testimony whereof I affix my signature.
JOHN W. COOKE.
